UNITED STATES PATENT OFFICE

OLAF LARSEN, OF FORT ATKINSON, WISCONSIN, ASSIGNOR TO THE CREAMERY PACKAGE MFG. COMPANY, OF CHICAGO, ILLINOIS, A CORPORATION OF ILLINOIS

REFRIGERATED AGITATING DEVICE

Application filed April 18, 1929. Serial No. 354,840.

The invention relates to combined refrigerating and agitating devices for use in liquid storage tanks, more particularly to the arrangement of the agitating blades in the 5 type of refrigerated agitator illustrated in the co-pending application of George E. Wallis and John C. Scovel, Jr., serial No. 137,417.

In the use of such devices for both cooling and agitating a liquid, such as milk, in a 10 storage container, circulation of the liquid is maintained by the device, the cooling being accomplished as the liquid passes the refrigerated drum or body of the device. Storage tanks for milk are constructed in a variety of 15 shapes and proportionate dimensions, and I have found that different shapes of agitator blades are best suited respectively to different shapes and sizes of tanks. As heretofore used, the blades have been fixed upon the 20 refrigerated drum, thus preventing the adaptation of any single device to either of several different tanks, and also retarding to some extent the free circulation of the liquid across the entire face of the drum.

25 The object of the invention is to provide, in a refrigerated agitator, a refrigerated body or drum carrying agitating blades mounted in spaced detachable relation thereto. Other objects and advantages will be apparent in 30 the following detailed description of a preferred embodiment of the invention.

Referring to the drawings, Fig. 1 is a side view of a refrigerated agitator drum with the agitating blades mounted in accordance 35 with the invention, a portion of the blades mounting being shown in section. Fig. 2 is a front view of the drum and blades. In the drawings the numeral 1 indicates a hollow drum adapted to contain in operation a circulating refrigerant. The drum is supported for rotation on a hub 2 adapted to receive a shaft (not shown) and through which the refrigerant circulation conduits enter the drum. A detailed description of the 40 construction and operation of the refrigerated drum being fully set forth and illustrated in the above mentioned co-pending application, it is considered not necessary to an understanding of the present invention to illustrate and describe such construction herein.

A stud 3 is secured, preferably by welding to the front face of the agitator drum at its axis of rotation, the constricted outer end 4 of the stud being screw threaded or otherwise adapted for the removable attachment of 55 a hub 5 upon which are fixed radial blades 6. The blades 6 herein illustrated are but one style of several which may be used to best advantage in several different types of tanks, and the mounting herein disclosed enables 60 the simple removal of one set of blades for replacement by another set of any desired design. The considerable space between the blades and the face of the drum permits the free flow of the liquid across the entire drum 65 face, with increased efficiency of the cooling effect upon the liquid, as against the cooling effect when the blades are mounted directly upon the face of the drum.

I claim as my invention:

1. A device of the class described comprising a rotatable cooling drum, a stud mounted axially upon the face of said drum, a hub detachably secured to said stud, and a plurality of radial blades mounted on said 75 hub in spaced relation to the face of said drum.

2. A device of the class described comprising a rotatable cooling drum, a plurality of radial blades rotatable with said drum and 80 positioned in spaced relation thereto, and means positioned axially of said drum and blades for detachably securing said blades to said drum.

3. A device of the class described comprising a rotatable cooling drum, and a plurality of radial blades having detachable mounting on said drum in co-axial spaced relation thereto.

In witness whereof I have hereunto attached my signature.

OLAF LARSEN.
